CARBURETOR

William J. McSpedon, III, Yonkers, N. Y.

Application October 16, 1946, Serial No. 703,651

3 Claims. (Cl. 261—59)

1

My present invention, in its broad aspect has to do with improvements in carburetors, and more particularly, it is my purpose to provide (1) an improved and unique vacuum or suction operated fuel feed thereby eliminating the usual pump mechanism for drawing fuel into the carburetor, (2) to facilitate aligning the operating lever and the like with the instrument board controls and the like, (3) to provide a novel and improved pressure release and adjustment to regulate the pressures built up in the mixing chamber to insure a uniform mixture, (4) to provide a novel and unique choke mechanism and throttle valve assembly, (5) to attain by reason of down draft operation a better, more efficient, cleaner, and more accurately adjusted air supply, and to utilize such down draft to create suction or a partial vacuum to draw in the fuel thereby eliminating the usual pump, and (6) to provide means for controlling the spark through the vacuum created in the manifold. In attaining the above and other important objects and advantages I make use of a novel and practical fuel inlet having a novel and improved head, under which are the fuel outlets, such being arranged in the air passage from the head of the carburetor which is movable to align the carburetor controls. The fuel reservoir is of constant level and is float controlled through an improved valve arrangement, and the downflow of air is guided and regulated by a choke mechanism, and the intake of fuel through an improved adjustable valve. In addition to the above, I provide novel supports and brackets for the control wires from the instrument board, and an improved general carburetor structure with an adjustable, rotatable head supporting the air cleaners, and an improved arrangement of the mixing chamber, and butterfly with the adjacent vacuum spark plug automatic control.

In addition to the above objects, advantages, and changes in structure, others will be herein-after apparent from the description and drawings, but it is understood that changes in form, size, shape, construction and arrangement of parts may be made within my broad inventive concept, and are within the scope of the appended claims.

In the drawings wherein I have illustrated a preferred form of my invention:

Figure 1 is a side elevation looking toward the side on which most of the controls are mounted;

Figure 2 is a vertical section through my carburetor taken with the carburetor disposed as in Figure 1;

2

Figure 3 is a side elevation with the carburetor turned 90° from the position shown in Figure 1;

Figure 4 is a vertical section with the carburetor disposed as in Figure 3;

Figure 5 is a vertical section with the carburetor turned 180° from the position shown in Figure 1;

Figure 6 is a top plan view;

10 Figure 7 is a top plan view with the adjustable air chamber and air valve removed;

Figure 8 is a top plan view with both the air chamber and the fuel chamber cover removed;

15 Figure 9 is a bottom plan view of the head for the fuel pipe;

Figure 10 is a top plan view of the head for the fuel pipe;

Figure 11 is a side view of the head for the fuel pipe;

20 Figure 12 is a section on the line 12—12 of Figure 2;

Figure 13 is a section through the pressure adjusting and relief valve;

25 Figure 14 is a top plan view of the fuel reservoir cover plate;

Figure 15 is a bottom plan view of the fuel reservoir cover plate;

Figure 16 is a top plan view of the air valve spring arm, and

30 Figure 17 is a side elevation of my improved float.

In the drawings wherein like characters of reference are used to designate like or similar parts throughout the several views:

35 The numeral 1 designates the intake manifold of an internal combustion engine to which is coupled by flanges 2 and bolts 3, the carburetor supporting sleeve 4 having a butterfly valve 5 interpolated therein, connected with the instrument panel by the usual wire 7. The butterfly valve 5 is mounted by screws 6 in a shaft 8 journalled in the bosses 8^a, Fig. 3, on the walls of the sleeve and carries at one end an operating lever 9. The lever 9 has a split hub 10 held in clamping engagement with the shaft 8 by a screw 11, and its throw is regulated by screws 12 and 13. Tapped into the sleeve 4 at the butterfly valve is a connection 14 to a vacuum control for the spark. The sleeve 4 is flanged at 15 to form stops for screws 12 and 13.

40 The upper end 16 of the sleeve 4 has the mixing chamber of the carburetor and is slightly enlarged at its top end at 17, Fig. 5, and provided with a circumferentially spaced wall 18

connected by a bottom 19 with the sleeve to provide a reservoir 20 which extends from a point slightly above the butterfly valve to the top of the sleeve. Tapped through the wall 18 and sleeve 4 near the bottom of the chamber or reservoir 20 is a tube 21 having a threaded end 22 and an enlarged head 23 formed with a needle valve seat 24 and inlet openings 25. Threaded into the enlarged head 23 is a needle control and idling adjustment valve 26 having a handle 27. Suitable wrench engaging formations 28 are provided on the head of the tube and needle valve assembly for ready attachment and removal.

Floating on the fuel within the chamber is a float 29 having a U-shaped arm 30 carrying a plate 31 pivoted in U-shaped bracket 32. The float 29 is reduced in thickness at 33 to clear the bracket 32, and the arm may be formed of wire—as shown in Figure 17—bent downwardly at right angles as at 34 and extending through the cork body of the float and beaded over at 35. The bracket 32 has a threaded base 36 engaging the threaded end of fuel inlet pipe 37. The end of the fuel inlet pipe is enlarged and formed with a valve seat 38. A freely slideable square needle valve 39 is held off the valve seat by the pressure of fuel in the line, and the distance which the valve is off its seat—the extent of opening thereof—is regulated by the float 29 through plate 31 which bears against the head of the valve. The fuel line 40 is coupled with the fuel intake pipe 37, and a wrench engaging formation 41 is provided. To a boss 42 on the wall 18 beneath and to one side of the formation 41 is attached by a screw 43 a bracket 44, one end of which is turned at right angles as at 45 and bears against the formation 41 and the other end of which carries a clamp 46 for the operating wire 7.

Seated upon a gasket 47 on the upper edge of the wall 18 or reservoir 20 is a fuel reservoir cover plate 48. The cover plate 48 has a flange 49, an annular rising side wall 50, a centrally located opening 51 and a downwardly sloping floor 52 from the wall 50 to the opening 51 which leads into the annular sleeve part 53 of the cover plate which fits into the enlarged upper end 17 of the mixing chamber 16. A threaded opening 54—see Figures 13, 14 and 15—is provided in the cover plate which communicates with the reservoir 20.

Removably and slidably mounted over the flange 49 and against the side wall 50 is a cylindrical head 55 which has a side wall 56 and a top 57 formed with a center opening 58 surrounded by an upstanding annular flange 59. A beveled part 60 at the point where the flange joins the top provides a seat for a plate valve 61 pinned to a rod 62 slidably received in a bored boss 63 on a transverse arm 64 formed on the flange 59. The bottom end of the rod 62 is seated in an opening 65 in a boss 66 on the downwardly curved arm 67 which is threaded at 68 to the pin 69 extending upwardly through the cover 57. A coil spring 70 extends about the rod 62 and bears against the bars 66 and plate valve 61 to hold the plate valve resiliently against its seat. Above the opening 58 and attached to the flange 59 is designed to be attached a conventional form of air strainer and cleaner (not shown). The pin 69 on which the arm 67 is attached has threaded to its upper end an adjusting nut 71, between which and a jam nut 72 on the pin 69 is an L-shaped lever 73 having a headed pin 74; by adjustment of the nut 71 the richness of the

mixture can be regulated as well as idling adjustments. A spring 75 on the pin 74 extends through a slot 76 in the lever and bears against the nut 71 to hold it in adjusted position. The lever 73 is pivotally attached by pin 74 to a bell crank lever 77. The pin 74 extends through an elongated slot 78 in one arm of the bell crank and the other arm is connected to the operating wire 79 to the instrument panel (not shown). An L-shaped bracket 80 is fixed to the head by the screws 81 and pivotally mounts the bell crank lever thereon by screw 82 so that when the operating wire is manipulated the bell crank is tilted to raise and lower the lever 73 and open and close the air valve 61.

Threaded in the opening 54 leading into the reservoir 20 through the cover is a pressure relief tube 83 which extends up through the head 54 and has outlets 84 through nut 85.

Engaged with the threaded end 22 of the fuel inlet tube 21 is an upwardly extending fuel inlet 86 which rises centrally of the fuel mixing chamber 16 to within the sleeve part 53. A head 87—shown in Figures 9, 10, and 11—is threaded over 25 connected with the end of the inlet 86 by a sleeve 88 carrying a flange 89 spaced from a downwardly beveled plate 90. In the web 91 between the flange 89 and plate 90 are angular outlet openings 92, and the plate is kerfed at 93 to receive a screw driver or the like for adjusting or removing the head. Suction created by the manifold causes air to be drawn down past plate valve 61 against the pressure of spring 70 and down and around the head 87 in the direction of the arrows. This suction draws fuel through inlet 86 and out through outlets 92 beneath the plate 90. The amount of fuel is adjusted by needle valve 26.

At the upper edge of the side wall 18 of the reservoir 20 are a plurality of laterally spaced bored bosses 94 through which extend the shanks 95 of upwardly extending clamping hooks 96. Hooks 96 seat in depressions 97 in the cylindrical head 55 to adjustably retain the head on the cover plate 48, and the cover plate 48 on the reservoir 20. The shanks are threaded as at 98 to receive nuts 99 by which the hooks are drawn down to clamp the head in place, or loosened up so that the head may be rotated or turned to align the operating levers and the like with the operating wires and instrument board or panel. While I have mentioned an instrument panel in connection with the present carburetor, it is emphasized that the carburetor is one of general utility for use with any internal combustion engine, and not necessarily with power plants for automobiles and the like having instrument panels.

In operation as the butterfly valve 5 is opened, air will be drawn down through the cover 55 and into the mixing chamber within the sleeve 4 to receive fuel leaving fuel inlet head 88. Air is directed over the head by the conical surface 52 of the reservoir cover which has a portion extending into the end of the mixing chamber sleeve 4. The head 88 lies within the depending sleeve or skirt portion of the cover 48. The fuel is supplied from a reservoir 20 over which the cover 48 extends. The cover 48 is formed to receive the air intake head 55 whereby to make for a compact and simple construction. At the bottom of the reservoir is a throttle valve fitting which extends into the mixing chamber and to which fuel inlet tube 86 is connected. The 75 By this means the fuel supply is controlled. The

float 29 in the reservoir operates on valve element 39 to maintain a constant supply of fuel in the reservoir. The float is of ring shape to surround the sleeve 4 and is cut away on one side so as to provide less material to keep that side afloat and consequently when the fuel supply drops the recessed side of the float will drop to a greater extent and the arm 30 with the plate 31 thereon will engage the valve element 39, the arm 30 lying within the recess formed in the float.

Air valve 51 is secured to rod 62 vertically slidable in a guide 63, Fig. 2, curved arm 67 receives and supports the lower end of rod 62. Spring 70 surrounds rod 62 and engages with valve 61 and the boss 66 of the arm 67. The outer end of arm 67 has a threaded connection with an operating rod 69. Lever 73 is adjustably connected to the upper end of rod 69 whereby the tension of the spring 70 to hold the valve in its closed position may be adjusted. The lever 73 is connected to bell crank lever 77 which is operated by wire 79 at the operator's station.

From the foregoing it is believed that the operation and advantages of my invention will be apparent, but it is again emphasized that interpretation of the scope of my invention should only be conclusive when made in the light of the subjoined claims.

I claim:

1. In a carburetor for the fuel supply of internal combustion engines, the combination which comprises a vertically positioned tubular casing, a spaced circumferential wall extended around the upper end concentric therewith and connected at its bottom edge to the outer surface of the casing at a point spaced from the upper end providing a float chamber around the upper end of the tubular casing, an annular wall having its lower edge positioned on the upper edge of the circumferential wall, a cylindrical head positioned on the upper edge of the said annular wall, a conical shaped floor having the lower end thereof sloping downwardly toward the center and having a depending sleeve extended from the central part of the lower end downwardly into the upper end of the tubular casing, said sleeve having an annular shoulder on the outer surface and said shoulder and outer surface of the sleeve fitted with the upper end and inner surface of the tubular casing, respectively, a fuel supply connection extended through the said circumferential wall and into the float chamber, a fuel inlet tube extended from the lower end of the float chamber into the tubular casing and upwardly in the tubular casing to a point spaced from the upper end thereof, said fuel inlet tube communicating with the float chamber, a manually actuated needle valve extended into the said fuel inlet tube for controlling fuel supply through the tube, said cylindrical head having a neck on the upper end thereof with a valve seat in the lower end of the neck, a valve in the lower end of the neck of the cylindrical head positioned to coact with the said valve seat, and means resiliently urging the said valve upwardly against the said valve seat.

2. In a carburetor for the fuel supply of internal combustion engines, the combination which comprises a vertically positioned tubular casing, a spaced circumferential wall extended around the upper end concentric therewith and connected at its bottom edge to the outer surface of the casing at a point spaced from the

upper end providing a float chamber around the upper end of the tubular casing, an annular wall having its lower edge positioned on the upper edge of the circumferential wall, a cylindrical head positioned on the upper edge of the said annular wall, a conical shaped floor having the lower end thereof sloping downwardly toward the center and having a depending sleeve extended from the central part of the lower end downwardly into the upper end of the tubular casing, said sleeve having an annular shoulder on the outer surface and said shoulder and outer surface of the sleeve fitted with the upper end and inner surface of the tubular casing, respectively, a fuel supply connection extended through the said circumferential wall and into the float chamber, a fuel inlet tube extended from the lower end of the float chamber into the tubular casing and upwardly in the tubular casing to a point spaced from the upper end thereof, said fuel inlet tube communicating with the float chamber, a manually actuated needle valve extended into the said fuel inlet tube for controlling fuel supply through the tube, said fuel inlet tube having a spray head on the upper end thereof and positioned in the depending sleeve of the cylinder head and said spray head having radially disposed upwardly extended orifices therethrough, said cylindrical head having a neck on the upper end thereof with a valve seat in the lower end of the neck, a valve in the lower end of the neck of the cylindrical head positioned to coact with the said valve seat, and means resiliently urging the said valve upwardly against the said valve seat.

3. In a carburetor for the fuel supply of internal combustion engines, the combination which comprises a vertically positioned tubular casing, a spaced circumferential wall extended around the upper end concentric therewith and connected at its bottom edge to the outer surface of the casing at a point spaced from the upper end providing a float chamber around the upper end of the tubular casing, an annular wall having its lower edge positioned on the upper edge of the circumferential wall, a cylindrical head positioned on the upper edge of the said annular wall, a conical shaped floor having the lower end thereof sloping downwardly toward the center and having a depending sleeve extended from the central part of the lower end downwardly into the upper end of the tubular casing, said sleeve having an annular shoulder on the outer surface and said shoulder and outer surface of the sleeve fitted with the upper end and inner surface of the tubular casing, respectively, a fuel supply connection extended through the said circumferential wall and into the float chamber, a float in said float chamber having means controlling the fuel supply through the said fuel supply connection, a fuel inlet tube extended from the lower end of the float chamber into the tubular casing and upwardly in the tubular casing to a point spaced from the upper end thereof, said fuel inlet tube communicating with the float chamber, a manually actuated needle valve extended into the said fuel inlet tube for controlling fuel supply through the tube, said cylindrical head having a neck on the upper end thereof with a valve seat in the lower end of the neck, a valve in the lower end of the neck of the cylindrical head positioned to coact with the said valve seat, and means resiliently urging the said valve upwardly against the said valve seat.

urging the said valve upwardly against the said valve seat.
